Specification for Design.

Patented Apr. 8, 1913.

Application filed November 5, 1912. Serial No. 729,654. Term of patent 3½ years.

To all whom it may concern:

Be it known that we, HERMANN SCHROFF, a subject of the German Emperor, a resident of the borough of Manhattan, city, county, and State of New York, (whose post-office address is 215 Manhattan avenue, Manhattan, New York city, New York,) and CHARLES J. CRONK, a citizen of the United States, a resident of Weehawken, county of Hudson, State of New Jersey, (whose post-office address is 1019 Boulevard East, Weehawken, Hudson county, New Jersey,) have invented a new, original, and ornamental Design for Textile Fabrics, of which the following is a specification, reference being had to the accompanying drawing, forming part thereof.

The drawing illustrates a portion of the fabric showing our new design.

We claim:

The ornamental design for a textile fabric, as shown.

HERMANN SCHROFF.
CHARLES J. CRONK.
